PREDETERMINED TORQUE RELEASE SOCKET WRENCH

Jacques P. Evans, San Antonio, Tex.

Application March 19, 1954, Serial No. 417,245

2 Claims. (Cl. 81—52.4)

This invention relates to tools and more particularly to a torque tool to be employed as a wrench.

It is an object of this invention to provide a torque wrench in which a positive indication of the torque applied to the nut or bolt to be tightened is felt when the torque reaches a predetermined value, and any further movement of the wrench to apply further torque to the bolt or nut merely results in the wrench being inoperative to transmit the torque to the nut or bolt.

It is a further object of this invention to provide a wrench which is designed to limit the torque applied in either direction, left or right, by a simple setting which predetermines the torque value which may be applied to the nut or bolt to be tightened and thereby prevents the application of unequal pressure to a plurality of nuts or bolts where a constant torque value or degree of tightness is desired, and at the same time avoids stripping the threads from the nut or bolt.

A still further object of this invention is to provide a torque wrench in which the parts have been properly hardened so that the wrench will not require frequent calibration, as is the case in many of the present torque wrenches, and in which the calibration of the wrench is easily effected and the wrench is adaptable to any range calibration in inch or foot pounds.

Another and still further object of this invention is to provide a torque wrench which may be manufactured to accommodate any present socket wrench drive by merely increasing or decreasing the size of the wrench.

Also, the torque wrench of the present invention is capable of economical manufacture, employs a minimum number of working parts so as to be compact, and which is rugged and capable of constant use over long periods without anticipation of failure in the function of the torque wrench. Further, the present torque wrench may be easily disassembled and assembled to replace any parts which may become worn with a minimum of effort and without the requirement of expert knowledge of mechanics.

Other objects and advantages will become apparent from the following detailed description, forming the specification, and taken in conjunction with the accompanying drawings, wherein:

Figure 1 is a top plan view of the torque wrench embodying this invention;

Figure 2 is a partial side elevational view of the wrench;

Figure 3 is a vertical sectional view through the housing and adjusting head, shown partially in elevation;

Figure 4 is a sectional view similar to Figure 3 but showing the parts within the housing in elevation;

Figure 5 is a fragmentary cross sectional view of the adjusting cap, showing its relation to the housing after having been rotated one full turn;

Figure 6 is a sectional view taken on line 6—6 of Figure 3;

Figure 7 is a sectional view taken on line 7—7 of Figure 3 and looking in the direction of the arrows;

2

Figure 8 is a sectional view taken on line 8—8 of Figure 3 and looking in the direction of the arrows;

Figure 9 is a fragmentary view, partially in section, showing the structure of the spring loaded balls carried by the squared end of the drive for engagement with a socket; and

Figure 10 is a fragmentary sectional view showing the structure of the slip clutch and attachment of the drive within the housing, on a somewhat enlarged scale, showing a modified structure.

With continued reference to the drawings, there is shown a torque wrench, generally indicated at 10, which comprises a housing, generally indicated at 12 of cylindrical shape and having an annular chamber 14 therein, and a handle 16 preferably integral with the housing and extending laterally outwardly therefrom. The elongated cylindrical handle 16 may be conveniently provided at its end remote from the housing 12 with a roughened or knurled portion 18 to provide a non-slip gripping surface for the hand of the user.

The housing 12 includes a body 20 of cup-shape having a cylindrical side wall and a circular bottom 22 formed integrally therewith and closing one end of the chamber 14 while the end of the body 20 remote from the bottom or end wall 22 is closed by a circular cap 24 which defines a face plate for the wrench 10 and is secured to the body 20 by screws 26 which are received in countersunk apertures in the cap or face plate 24 and enters registering tapped openings in a flange 28 formed annularly about the end of the body 20 at the end thereof remote from the end wall 22 and directed inwardly therefrom so as to project into the chamber 14. Thus, the cap or face plate 24 is secured upon the body 20 of the housing 12 to close the open end thereof and to thereby close the other end of the chamber 14.

The cap or face plate 24 is provided with a central threaded opening transversely therethrough, indicated at 30, which threadingly receives the externally threaded shank or plug 32 dependently carried centrally upon an adjusting head, generally indicated at 34 so as to normally maintain the circular indexing plate or flange 36 in spaced parallel relation overlying the outer surface of the cap or face plate 24. The top surface 25 of the cap or face plate 24 is provided about its periphery with spaced inscribed index markings or lines 38 to indicate torque force in inches or foot pounds with the markings 38 stepped in increments of ten units of measurement and preferably each line or mark indicated with a numerical figure. The cap or face plate 24 also is provided upon its top surface 25 with a plurality of shallow depressions or concavities 40 with one of the depressions or concavities 40 in alignment with one of the markings or lines 38 and adapted to receive therein the spring loaded plungers 42 and 44 carried in diametrically opposed relation by the plate or flange 36 in respective bosses 46 and 48 formed integrally with the plate 36 and upstanding therefrom. The central knob or boss 50 is also formed integrally as a part of the adjusting head 34 and is upstanding from the plate or flange 36 so as to form or provide a central hub therefor which is adapted to be gripped by the fingers of the user to rotate the adjusting head 34 with relation to the housing 12 and specifically with relation to the cap or face plate 24. The plate or flange 36 is further provided with a triangular projection or pointer 52 extending outwardly therefrom at a point about its periphery so as to register with the markings 38 to give a reading in the units of measure employed as the adjusting head 34 is rotated in clockwise direction from a stop 54 formed as a post or extension of one of the screws 26 adjacent the handle 16 and projecting upwardly from the top thereof so as to project beyond the upper or outer top surface 25 of the face plate

24 and is disposed also along the longitudinal center line of the handle 16. The stop 54 determines the starting position from which the adjusting head 54 may be rotated, and limits the rotation of the adjusting head to approximately one full turn since the pointer 52 will contact the stop 54 in its path of movement.

The end wall 22 of the housing 12 is provided with a central transverse opening 56 therethrough defining a bearing and having an enlarged annular recess 58 in which is accommodated a collar 60 formed on the shank 62 of a socket wrench drive or driving member, generally indicated at 64. A squared end 66 of the driving member or drive 64 projects outwardly from the outer face of the end wall 22 and in perpendicular relation thereto extending along the longitudinal axis through the housing 12 and the chamber 14. The squared end 66 has the usual spring pressed ball 68 (see Figure 9) adjacent the terminal end thereof to define securing means whereby a socket wrench may be detachably secured onto the squared end 66 which defines a wrench socket receiving member.

The drive 64 extends into the housing 12 and has its longitudinal center line coincident with the longitudinal center line through the housing 12 and the chamber 14 so that the major portion of the drive is disposed within the chamber 14 coaxially thereof. The upper cylindrical shaft portion 70 of the drive 64 is rotatably received within the closed bore 72, defining another bearing for the drive, which opens to one end of the shank 32 of the adjusting head 34 remote from the knob 50 into the chamber 14 of the housing 12.

In order to maintain the drive or driving member 64 in the housing 12 against longitudinal movement relative thereto, there is provided a retainer plate 74 having a central opening or recess 76 in coaxial with the opening 56 and opening through the inner face thereof to rotatably receive the shank 62 of the drive 64 which extends beyond the collar 60 to the side thereof remote from the squared end 66, and also has a plurality of spaced countersunk openings therethrough to receive therein screws 78 which enter registering tapped openings in the internally raised annular boss 80 formed integrally with the wall 22 so as to secure the retainer plate to the surface of the boss 80 remote from the outer face of the end wall 22. It will be noted that the boss 80 is of a lesser diameter than the chamber 14 and extends therewithin and the retainer plate secured thereon is adapted to engage the side of the collar 60 remote from the side adjacent the squared end 66 so as to retain the drive 64 in the housing 12 against longitudinal movement relative to the housing.

The retainer plate 74 is circular in outline and is received within the central annular opening 82 formed in the circular slip clutch plate 84 formed as a part of the boss 80 with the thickness of the retainer plate being less than that of the boss 80. The clutch plate 84 is provided along its flat face remote from the end 22 with a plurality of teeth 86 which are adapted to engage with the teeth 88 formed along the periphery of the circular clutch plate 90 which is disposed in overlying relation to the clutch plate 84 and is of the same diameter, the diameters of the clutch plates 84 and 90 being the same as the diameter of the boss 80 formed on the end wall 22.

A clutch plate 90 is provided with a square opening 92 therethrough which is coaxial with the openings 56 and 76 to receive therein a squared section 94 formed on the drive 64 between the shaft portion 70 and the shank 62 and extending from adjacent the top surface of the retaining plate 74 to beyond the end face of the clutch plate 90 remote from the end face carrying the teeth 88. Thus, the drive 64 is operatively connected to the clutch plate 90 thereby permitting the movement of the clutch plate 90 with the rotation of the drive 64 as the wrench is applied to the nut or bolt (not shown) to be tightened.

A coil spring 96 surrounds the drive 64 and is seated

on the end face of the clutch plate 90 remote from the end face carrying the teeth 88 and is retained at its other end by a washer 98 carried on the shaft portion 70 of the drive 64 adjacent the inner surface of the cap or face plate 24. It will be noted that the end face of the externally threaded shank 32 of the adjusting head 34 will contact the surface of the washer 98 remote from the surface against which one end of the coil spring 96 bears. The coil spring 96 is preloaded by the use of a washer 98 so that it resiliently urges or yieldingly moves the clutch plate 90 into engagement with the clutch plate 84 and the spring load of the spring 96 may be increased by rotating the adjusting head 34 in a clockwise direction to a value indicated by the markings 38 on the top surface 25 of the face plate 24. The action of the adjusting head 34 when rotated in a clockwise direction to load the spring 96 to a predetermined value has been fully discussed hereinbefore with respect to the action of the spring urged pins or plungers 42 and 44 and their successive engagement in the concavities 40 to not only indicate movement to successive lines or markings 38 but also to retain the adjusted position against displacement.

It will be appreciated, that the initial preloaded value of the coil spring 96 may be changed by the addition of more washers 98 whereby the markings 38 will be correspondingly changed in their value in direct proportion thereto, and in proportion to the spring loading on the spring 96.

When the torque wrench 10 is put in use to tighten a nut or bolt, and a suitably sized socket wrench, not shown, is detachably secured onto the squared end 66 of the drive 64, the knob 50 of the adjusting head 54 may be gripped by the fingers of the operator and the adjusting head rotated in a clockwise direction to indicate the amount of torque he wishes to apply to the nut or bolt to be tightened. As hereinbefore indicated, rotation of the adjusting head 34 in a clockwise direction will cause compression of the coil spring 96 to a value indicated by the index defined by the markings 38 with the pointer 52 indicating the exact degree of compression imparted to the spring 96. The spring 96 in turn transmits this predetermined resilient loading to the clutch plate 90 to advance the clutch plate 90 into engagement with the clutch plate 84 so that the mating teeth on the respective clutch plates are in mesh or engagement. The torque wrench, with the suitably sized socket secured upon the squared end 66 of the drive 64 will then be placed over the nut or bolt to be tightened, the knurled portion of the handle 16 then grasped by one hand of the operator and the housing rotated in the proper direction, depending on whether the threading of the nut or bolt is right or left-handed, so that the movement of the handle will cause rotation of the housing 12 and the drive 64 due to the operative connection between the drive and the clutch plate 90. The rotation of the handle and housing will be continued to be imparted to the drive 64 until such time as the torque necessary to further tighten the nut or bolt to which the wrench is applied is equal to the resilient load selectively placed upon the spring 96. When these values are equal, or when the torque necessary to further tighten the nut or bolt to which the wrench is applied exceeds the resilient loading of the spring 96, the clutch plate 90 will have its teeth 88 ratchet about the teeth 86 of the clutch plate 84 since the loading in the spring 96 will not be sufficient to hold the teeth 86 and 88 in engagement. Any further movement of the wrench handle 16 in an effort to further tighten the nut or bolt to which it is applied will merely result in the slip action of the clutch defined by the clutch plates 84 and 90 and the drive 64 will not have any further rotation imparted thereto by rotation of the handle and housing of the torque wrench 10. It should be pointed out, that the drive 64 is freely rotatable within the housing 12.

In the resulting ratchet action between the clutch plates 84 and 90, this ratcheting will be transmitted

through the housing 12 to the handle 16 and easily felt by the hand of the operator, who then will be apprised of the fact that the nut or bolt to which the torque wrench 10 has been applied is no longer operative to further tighten the nut or bolt and the degree of tightness is in accordance with the predetermined value selectively present by rotation of the adjusting head 34.

The illustration in Figure 5 shows the relation of the lower surface of the flange 28 of the adjusting head 34 with the top or outer surface 25 of the face plate 24 when the adjusting head has been rotated to its maximum, that is one full turn in a clockwise direction, to show that a clearance will still be maintained between the joining faces of the flange 28 and the top surface 25 of the face plate 24. Thus, it will be apparent that there is sufficient clearance provided between the flange of the adjusting head and the top surface of the cap or face plate 24 to permit rotation of the adjusting head to one full turn.

To sum up the operation of the torque wrench 10, the socket, not shown, is secured to the drive 64 at the squared end 66 thereof and the adjusting head 34 is set to the desired torque which exerts tension on the spring 96 which is transmitted to the clutch plate 90. As the handle 16 is turned to tighten the nut or bolt, the teeth 86 and 88 will remain engaged until the torque is set on the spring 96 by the adjusting head 34 obtains, at which time the drive 64 will remain stationary and any further movement of the handle 16 will cause the clutch plate 84 formed as an integral portion with the boss 80 at its end remote from the outer face of the end wall 22, to rotate pushing the clutch plate 90 away therefrom thereby causing the operator to feel the ratcheting movement resulting between the clutch plates when the preset torque value has been reached.

Thus, it will be noted that the clutch plate 84 is built in the housing 12 and will rotate therewith.

From the foregoing, it will be apparent that there has been provided a torque wrench 10 which comprises a rotatable housing 12, the housing 12 including a body 20 having a chamber 14 therein open at one end and a face plate 24 detachably secured to said body to close the one open end of the chamber 14, an adjusting head 34 rotatably carried on the plate 24, a drive 64 rotatably carried by the housing 12 and disposed within the body 20 in the chamber 14 coaxially with the longitudinal center line through the body and housing and having a socket receiving end 66 projecting beyond the body at the closed end 22 thereof remote from the open end, a fixed clutch plate 84 carried by and formed integrally with the body 12 and disposed within the chamber 14, a movable clutch plate 90 disposed within the chamber 14 and operatively connected to the drive 64, yielding means in the form of the coil spring 96 operatively connected between the movable clutch plate and the adjusting head 34 to urge the movable clutch plate into engagement with the fixed plate, the adjusting head 34 being rotatable to selectively preset the loading of the yielding means 96 to cause rotation of the movable clutch and be imparted to the drive 64 until the applied torque is equal to the preset value. Also, there is means defined by the retainer plate 64 disposed within the chamber 14 and carried by the body 20 to retain the drive 64 against longitudinal movement with respect to the housing 12. Also, the plurality of markings 38 inscribed upon the face plate 24 on the outer face 25 thereof defines a dial and a pointer 52 carried by the adjusting head 34 to cooperate with the dial to indicate the amount of load placed upon the yielding means 96. The face plate 24 and the adjusting head 34 also carry interengageable means, defined by the spring pressed plungers 42 and 44 and the concavities 40, to maintain the setting of the yielding means 96 imparted thereto by rotation of the adjusting head 34 to a predetermined value indicated upon the dial defined by the

markings 38, against displacement from the selected preset position of the adjusting head 34.

It should be pointed out that the yielding means, coil spring 96, urges the movable clutch plate 90 into engagement with the fixed clutch plate 84 whereby the movable plate will be rotated upon rotation of the housing 12.

In the modified structure shown in Figure 10, that part of the boss 80 formed as a circular slip clutch plate 84 has been replaced by a separate slip clutch gear 85 having formed therein teeth 87 adapted to mate teeth in the clutch plate or gear 90. The teeth 87 of the slip clutch gear or plate 85 are arranged annularly about and define the wall of a recess 89 formed in the top of the slip clutch gear or plate 85. A plurality of screws 78' are received in equally spaced openings about the recess 89 and extend therethrough into suitably tapped openings in register with suitably tapped openings in the boss 80' formed on the end wall 22. The boss 80' being of lesser height than the boss 80 in the form of the invention shown in Figures 1 through 9. It will also be noted that the openings through the slip clutch plate 85 wherein the plurality of bolts or screws 78' are received, are countersunk so that the heads of the screws 78' will not project above the surface of the recess 89.

The operation of the modified form of the invention shown in Figure 10 will be essentially the same as that of the torque wrench of Figures 1 through 9, and in addition, it will be apparent that the slip clutch plate or gear 85 will be capable of removal from the chamber 14 in the housing 12.

While there are shown and described the preferred embodiment of the invention, it is to be understood that the structure is susceptible to change and modification within the practicability of the invention and therefore should be limited only by the scope of the claims appended hereto.

What is claimed is:

1. A torque wrench comprising a hollow cylindrical body having a bottom wall closing one end thereof, a boss on the inner surface of said bottom wall extending into said body in concentrical relation about the longitudinal axis of said body to define a fixed clutch member, a cap closing the other end of said body, said bottom wall having an opening transversely therethrough concentric about the longitudinal length of said body, a plug thereadedly engaged in said cap in axial alignment with said opening and for advance through said plug toward said fixed clutch member, said plug having a socket therein opening through the end thereof adjacent said bottom wall and in axial alignment with said opening to define along with said opening in said bottom wall spaced axial aligned bearings, a drive member mounted in said bearings for rotation about its longitudinal axis, a rotatable clutch member mounted on said drive for rotation therewith and movement longitudinally thereof into frictional engagement with said fixed clutch member, a disc mounted on said drive for movement longitudinally thereof and engageable by said one end of said plug for movement longitudinally of said drive as said plug is advanced through said cap, a compression coil spring wrench concentrically about said drive member and engaging said rotatable clutch member into said disc at its opposite ends, a knob carried by said plug at its other end remote from said socket whereby rotation imparted to said knob will cause said plug to be advanced through said cap toward said fixed clutch member, spring loaded plungers carried by said knob and engaging said plug for maintaining said knob in a selected position of rotation and maintaining said spring under a selected tension imparted thereto by the advance of said plug and movement of said disc longitudinally of said drive member to place said rotatable clutch member into frictional engagement with said fixed member under the selected tension, and a handle connected to said body for imparting rotation thereto to cause rotation of said drive through said fric-

tionally engaged clutch members until a torque applied to said drive equals the preset tension of said spring.

2. A torque wrench comprising a hollow cylindrical body having a bottom wall closing one end thereof, a boss on the inner surface of said bottom wall extending into said body in concentrical relation about the longitudinal axis of said body to define a fixed clutch member, a cap closing the other end of said body, said bottom wall having an opening transversely therethrough concentric about the longitudinal length of said body, a plug threadedly engaged in said cap in axial alignment with said opening and for advance through said plug toward said fixed clutch member, said plug having a socket therein opening through the end thereof adjacent said bottom wall and in axial alignment with said opening to define along with said opening in said bottom wall spaced axial aligned bearings, a drive member mounted in said bearings for rotation about its longitudinal axis, a rotatable clutch member mounted on said drive for rotation therewith and movement longitudinally thereof into frictional engagement with said fixed clutch member, a disc mounted on said drive for movement longitudinally thereof and engageable by said one end of said plug for movement longitudinally of said drive as said plug is advanced through said cap, a compression coil spring wrench concentrically about said drive member and engaging said rotatable clutch member into said disc at its opposite ends, a knob carried by said plug at its other end remote from said socket whereby rotation imparted to said knob will cause said plug to be advanced through said cap toward said fixed clutch member, spring loaded plungers carried by said knob and engaging said plug for maintaining said knob in a selected position of rotation and maintaining said spring under a selected tension imparted thereto by the advance of said plug and move-
